UNITED STATES PATENT OFFICE.

SAMUEL L. SNEIERSO, OF BOSTON, MASSACHUSETTS, ASSIGNOR TO INDEPENDENT
BUTTON FASTENER MACHINE COMPANY, OF BOSTON, MASSACHUSETTS, A CORPORA-
TION OF MASSACHUSETTS.

HEEL.

1,123,941.

Specification of Letters Patent.

Patented Jan. 5, 1915.

Application filed June 14, 1912. Serial No. 703,654.

To all whom it may concern:

Be it known that I, SAMUEL L. SNEIERSO, a citizen of the United States, residing at Boston, county of Suffolk, Commonwealth 5 of Massachusetts, have invented certain new and useful Improvements in Heels, of which the following is a specification.

This invention relates to rubber heels and particularly to an armored heel in which 10 the rubber is protected and the heel reinforced by a metallic frame.

Rubber heels have frequently proved unsatisfactory for wearers who tend to run over their shoes. This has caused the heel to 15 wear away in one place and finally under the strain of unequal tread to become laterally displaced and distorted.

The construction and effect of my device will be more fully described in the speci- 20 fication which follows.

In the drawings which form a part of that specification, I have shown a heel with a form of reinforcement which I have found well adapted to practical use and well adapt- 25 ed to the end of commercial production.

Throughout specification and drawings like reference numerals are employed to indicate corresponding parts and in the drawings:—Figure 1 is a view of the bottom sur- 30 face of a rubber heel, Fig. 2 is a sectional view along the line 2—2, Fig. 1, Fig. 3 a plan view of the plate, and Fig. 4 an edge view of the same.

My heel comprises a molded rubber heel 35 blank 1 having embodied in it a plate consisting of a marginal wear receiving flange 2 with an inwardly extending plate 3 set in a different plane and lodged within the rubber of the heel. The plate 3 has a central 40 opening 7 through which the rubber of the heel 1 is molded to hold the plate in place. The frame is provided with openings 4' for the passage of screws 4, and openings 6' for the passage of the screws 6. The screws 6 45 engage threaded openings in a plate 5 set on the upper surface of the rubber heel which is to come next to the leather lifts of the ordinary heel of the shoe as indicated at H in dotted lines.

The wear plate 2 overhangs the portion 3 50 leaving the shoulder 8 which is also em- bedded in the rubber of the heel, as indicated in Fig. 2. The fastening screws 4 for attaching the rubber heel and the plates to the leather lifts pass through the openings 55 4' in the frame 3 and pass just outside of the edges of the triangular plate 5, which is set in the opposite direction to the general triangular frame 3 which permits of the fastening together of these two plates by 60 the screws 6 without the necessity of fasten- ing the screws 4 through the plate 5 and attaching the rubber heel to the shoe. It will thus be seen that the plate 3 is not only firmly held by its lodgment in the heel and 65 its complete envelopment and penetration by the molded rubber, but it is braced by the upper plate 5 which is backed by the non- resilient lifts of the leather heel. The screws 70 6 which unite these plates 3 and 5 make a cage or frame which supports the heel and prevents it from "running over."

The embedding in a molded body of rubber of a wear resisting plate having an opening in it with the body of the rubber passing 75 through the opening is capable of a great variety of uses.

While I have particularly described my invention as applied to rubber heels it is obviously capable of application to many 80 other articles, as automobile tires and other like articles which require strengthening and protection.

Various modifications in the structure and form of my device may obviously be made, 85 all without departing from the spirit of my invention if within the limits of the appended claim.

What I therefore claim and desire to se- 90 cure by Letters Patent is:

A detachable cushion heel adapted to be fastened to a heel and comprising a molded rubber body, an open substantially triangular wear frame set in said body, said frame having an offset marginal wear portion dis- 95 posed in the tread plane of the rubber body and a laterally disposed lug projecting into the opening defined by the sides of the

frame, said lug and frame sides pierced for fastenings, and a substantially triangular supporting plate set against the heel proper in opposite relation to said frame and secured to said frame by fastenings passing through said openings in the frame sides and lug.

In testimony whereof I affix my signature in presence of two witnesses.

SAMUEL L. SNEIERSON.
